HANDLE FOR KITCHEN IMPLEMENTS OR SIMILAR ARTICLES

Charles A. Rowley, 7803 E. Harper Ave., Downey, Calif.

Filed Feb. 1, 1963, Ser. No. 73,397

Term of patent 14 years

(Cl. D44—29)

FIG. 1.

FIG. 2.

FIG. 3.

FIG. 4.

FIG. 5.

FIG. 1 is a front elevational view of a handle for kitchen implements or similar articles showing my new design;

FIG. 2 is a side elevational view thereof;

FIG. 3 is a rear elevational view thereof;

FIG. 4 is a sectional view taken on line 4—4 of FIG. 1; and

FIG. 5 is a sectional view taken on line 5—5 of FIG. 1.

I claim:

The ornamental design for handle for kitchen implements or similar articles, as shown.
